ADJUSTABLE PROPELLER

Hans Reissner, Berlin-Charlottenburg, Germany

Application September 9, 1936, Serial No. 99,933
In Germany September 12, 1935

8 Claims. (Cl. 170—163)

My invention relates to adjustable propellers in which the reaction device for deriving the adjustment forces from the rotation of the propeller shaft is formed by an air blade brake or similar device which is disposed on the propeller side opposite the propeller bearing.

One object of my invention is to produce an adjustable propeller in which the air brake shaft drives two gears rotating in opposite directions, which gears can be coupled alternatively to the blades of the propeller so as to increase or decrease the pitch of said blades. According to my invention the gears are constructed as bevel gears rotatable on an adjustment shaft disposed transversely of the propeller shaft. Another object of my invention is to provide couplings between the gears and the propeller blades which cannot become jammed under the influence of the centrifugal forces set up by the rotation of the propeller. For this purpose my device is constructed with friction couplings axially displaceable on the transverse adjustment shaft. In a further development of my invention, the couplings are either directly connected with the centrifugal masses or they are formed themselves as centrifugal masses.

A further object of my invention will be seen from the following specification and claims.

My invention is illustratively exemplified in the accompanying drawings in which:

Figs. 1 and 2 are a longitudinal section and a part front view, respectively of the gearing of an oil controlled embodiment of my invention.

Fig. 1a shows a modification of the coupling mechanism, illustrated in Fig. 1, likewise in longitudinal section.

Figs. 3 and 4 are a longitudinal section and a part front view of a mechanical embodiment controlled by a centrifugal regulator or governer.

Fig. 5 is a longitudinal section of an embodiment with a centrifugal governor and friction-couplings.

Fig. 6 is a partial longitudinal section of a construction with worm engagements instead of couplings.

According to Figs. 1 and 2 blade bases 3 are disposed rotatably in bearings 1 of a boss-part 2. Worms 5 engage in worm wheels 4 of the blade bases, and further worm-wheels 6 on the shafts of worms 5 are engaged by worms 7 on a cross shaft 8 carrying medially thereof a worm-wheel 9. The worm wheel 9 is engaged by a worm 10 of a transverse adjusting shaft 11. The adjusting-shaft 11 carries rotatably thereon bevel-wheels 12, 13 permanently engaged by a bevel-

wheel 14 on a brake blade shaft 15, which latter is disposed freely rotatable in a nave-projection 16 and carries a nave hood 17 with brake-blades 18. The brake-blades 18 are constructed as screw-blades with a pitch opposite to that of the propeller-blades, whereby a rotation of the adjusting implement may be derived from the passage-wind of the flying aeroplane when the propeller is at rest.

The bevel-wheels 12, 13 may be coupled alternatively to the adjusting shaft 11. For this purpose the bevel-wheels are provided with bevel-coupling-surfaces 19, 20 and with movable cones 21, 22, constructed as pistons within cylinders 23, 24 of the bevel wheels. The cones 21, 22 are axially slidable but not rotatable relative to the adjusting shaft. Conduits 25 for oil under pressure are so connected by rotary stuffing-glands to the hollow-bored ends of the adjusting shaft 11, that they conduct the oil under pressure into the space behind the coupling-pistons 21, 22 and the couplings can thereby be thrown into engagement. The pressure-oil conduits 25 are connected to the controlling conduits leading to the pilot's place or cockpit by oil channels in the propeller bearings or by special introducing rings in any usual manner, so that the pilot can increase or decrease the propeller-pitch optionally by employing the motor oil pressure pump or a different oil-supply.

Instead of the cylinders 23, 24 for oil under pressure electric coils 28' can be provided, as shown in Fig. 1a, and the conduits 25 for the oil under pressure are then replaced by electric leads 25' with slip-ring connection 25² to the pilot's place. In this arrangement the coupling can be effected by electro-magnetic displacement, the coupling cones 21, 22 being constructed of suitable material.

In all cases the manipulation of the regulating conduits 25 can be automatically effected instead of by hand by a centrifugal regulator or governer affixed to the motor or by a special regulator, and the regulator can eventually be disposed on the propeller so that only a single conducting means 40 for oil under pressure or for electricity need be led into the propeller.

According to Figs. 3 and 4 the blade-bearings 1, 2, 3 and their worm-wheels 4 are substantially the same as in the previous construction. However, worms 5a both engage the worm-wheels 4 on the free propeller side, and worm-wheels 6a on the shaft of worms 5a engage worms 7a on a short intermediate shaft 8a. An additional worm-wheel 9a disposed centrally of the shaft 8a en-

gages a worm 10a on the adjusting shaft 11a, which, in the embodiment of Figure 3, extends transversely of the blade-axis of the propeller. For the drive of the adjusting shaft there are provided bevel wheels 12a, 13a in engagement with a wheel 14 disposed on the brake-blade shaft 15. The bevel wheels 12a, 13a are disposed independently of the adjustment shaft 11 in bearings 26 on the nave 2, so that they leave said shaft unaffected as long as the coupling 21a, 22a, constructed as a jaw-coupling, is not thrown into gear. The throwing into gear in one direction or another is effected automatically by a centrifugal regulator, the spindle of which is formed by the adjusting shaft 11a itself, which carries a centrifugal weight 27. The weight 27 is so compensated relative to the nave part 2 by a governor spring 28, that it keeps the two couplings 21a, 22a out of engagement at the desired standard speed of revolution while it engages the coupling for increase or decrease of pitch upon over- or under-stepping of said standard speed.

In order to automatically terminate the adjustment of the blades when the smallest permissible pitch positions have been reached the blade base 3 is provided with a projection 29 opposite a ram 30 displaceably disposed in the nave 2. The ram 30 actuates a two armed lever 31, which presses axially on the adjusting rod 11a in the direction of the centrifugal force of the regulator weight 27. This disengaging device thus uncouples the coupling 21a, as soon as the smallest permissible pitch has been reached.

According to Fig. 5 the blade root parts and their bearings are essentially the same as in the previous figures. The couplings are bevel-couplings 21b, 22b, which are disposed axially movable and secured against rotation on the adjusting rod 11b which is fixed against axial displacement not axially movable. The adjusting rod 11b is formed as a hollow shaft traversed by axially displaceable regulating rams 32, 33 carrying centrifugal weights 34, 35 and regulator springs 36, 37 on the end portions thereof projecting from said hollow shaft. The spring 37 abuts against the brake 37' rigidly supported on the propeller hub. As both rams 32, 33 are drawn outwardly by the centrifugal force, the coupling 21b of the one ram is coupled outwardly and the coupling 22b of the other ram is uncoupled outwardly, whereby both couplings are put out of engagement at a chosen standard, and upon over or under stepping of said speed the one or the other gear is thrown into engagement for increasing or decreasing the pitch.

The centrifugal weight 34 operating on increasing the pitch is of magnetizable material, and surrounded by a solenoid coil 38, which can be fed from the pilot's seat with an electric current through a regulating resistance. If this coil is fed with increasing current, it draws the centrifugal weight 34 increasingly outward, so that the coupling 21b operating on increase of pitch, can be brought into action by centrifugal displacement of the weight 34 on a speed of the propeller insufficient to cause increase of the pitch and the propeller is adjusted to a smaller standard speed. For the centrifugal weight 35 operating on the decrease of slope an electric control is unnecessary, because the adjustment of the blades to the smallest permissible pitch always remains harmless. As an uncoupling device for the smallest pitch a toothed rack ram 39 is provided which is axially moved by an intermediate worm 40, so as to bring a projection 41 on the ram 39 into

engagement with a flange 42 of the coupling 21a on the attainment of the smallest pitch, thereby disengaging the coupling.

In the embodiment illustrated in Figure 5, the whole main part of the adjusting device is disposed in a special housing 43, which is removable with the whole gear from the nave 2. This arrangement allows for attaching different kinds of regulating devices to one and the same propeller, corresponding to different requirements for special objects.

According to Fig. 6 worms 5a and worm wheels 6a lead from the blade worm-wheels 4 to two transverse worms 44, which are connected with worm-wheels 45. The worm-wheels 45 are constructed similarly to spur wheels, so that they can come into engagement as well with right-handed as with left-handed worms. Between these wheels a right-handed worm 46 and a left-handed worm 47 are disposed on a shaft 48, which is disposed axially movable but not rotatable in the hollow blade brake shaft 15a. Two magnetic coils 49, 50 are provided in the nave projection 16 and there between the axially movable shaft 48 carries an armature 51 so that by current supplied at choice to the coil 49 or 50 the worm 47 or 46 can be thrown into engagement and the adjusting device can be rotated in one or the other direction.

The two adjusting wheels 45 may be connected with each other by immediately interengaging gears 52, 53 for exact synchronization so that always each of the worms 46, 47 engages in uniform manner with them.

The switching in of the magnetic coils 49, 50 can be effected in all kinds of ways already mentioned, e. g. by hand through slip-rings or by a regulator through slip-rings or by a regulator mounted directly within the propeller.

I claim:

1. An adjustable propeller, comprising a propeller shaft, a hub, propeller blades rotatably arranged on said hub, a brake shaft parallel to the propeller shaft and rotatably supported by said hub, an air blade brake on said brake shaft, an adjusting shaft rotatably carried on said hub transversely of said propeller shaft, two gears rotatable on said adjusting shaft, means on said brake shaft to drive said gears in opposite directions, coupling means comprising two coupling elements axially displaceable on said transverse shaft and adapted to engage said gears respectively to transmit the movement of either of said gears at choice to said transverse shaft and a gearing mechanism to transmit the rotation of said transverse shaft to said propeller blades, whereby the pitch of the latter can be increased and decreased, respectively.

2. An adjustable propeller, as claimed in claim 1, in which said axially displaceable coupling elements on said transverse shaft comprise a sufficient mass to be displaced by centrifugal force at a predetermined speed of propeller revolution.

3. Adjustable propeller as claimed in claim 1, wherein said two gears are formed as bevel gears and said driving means on the brake shaft consists of a third bevel gear in engagement with said first-mentioned bevel gears.

4. Adjustable propeller as claimed in claim 1, wherein said coupling means comprises further electromagnetic means adapted to bring one of said coupling elements in engagement with the corresponding gear.

5. Adjustable propeller as claimed in claim 1, wherein said coupling means comprises further a centrifugal governor controlling said coupling ele-

ments, whereby one of said elements engages the corresponding gear, when the rotation of the propeller exceeds a predetermined speed and the other coupling element engages the second gear, 5 when the propeller rotation drops below said predetermined speed.

6. Adjustable propeller as claimed in claim 1, comprising further a governor including a centrifugal mass to automatically control said coupling means in dependence on the revolution 10 speed of the propeller and electromagnetic means adapted to displace said centrifugal mass in the centrifugal direction, at low revolution speeds of the propeller.

15 7. Adjustable propeller as claimed in claim 1, comprising further a movable control element

operatively connected with the gearing mechanism transmitting the rotation of said transverse shaft to the propeller blades, said movable control element being constructed and arranged to disengage said coupling means from the corresponding gear on attainment of the lowest permissible pitch.

8. Adjustable propeller as claimed in claim 1, 10 wherein the gearing mechanism transmitting the rotation of said transverse shaft to the propeller blades includes transverse worms and worm gears on the blade roots engaged by said transverse worms, and the entire adjusting device including said transverse worms is removably secured to the propeller.

15 HANS REISSNER.
